UNITED STATES PATENT OFFICE.

EDWARD W. GROGAN, OF BYERS, TEXAS, ASSIGNOR OF ONE-FOURTH TO WILLIAM R. STONE, OF WICHITA FALLS, TEXAS.

LATCH FOR GRAIN-CAR DOORS.

1,257,849.

Specification of Letters Patent. Patented Feb. 26, 1918.

Application filed December 9, 1916. Serial No. 136,047.

To all whom it may concern:

Be it known that I, EDWARD W. GROGAN, a citizen of the United States, residing at Byers, in the county of Clay and State of Texas, have invented certain new and useful Improvements in Latches for Grain-Car Doors, of which the following is a specification.

This invention relates to grain car doors and has for its object the provision of an inexpensive door which may be applied to any grain car and easily locked in either its open or closed position.

Other incidental objects of the invention will appear as the description of the same proceeds and the invention consists in certain novel features which will be particularly pointed out in the claims following the detail description.

20 The invention is illustrated in the accompanying drawings, in which—

Figure 1 is an elevation of my improved grain car door, showing the same in its closed position and viewing it from the inside of the car;

Fig. 2 is a similar view, showing the door in its open position;

Fig. 3 is an elevation looking at the outer side of the door;

30 Fig. 4 is a detail perspective view of the bolt and the operating members immediately adjacent the same;

Fig. 5 is a detail transverse section taken in the plane indicated by line 5—5 in Fig. 1, the bolt-controlling lever being in raised position;

Fig. 6 is a detail perspective view of the pivot mounting for the door;

Fig. 7 is a detail section of the same.

40 The car 1 may be of any preferred or usual construction. Adjacent the door opening in the side of the car, I pivotally mount my improved grain door 2 which is adapted to swing in a vertical plane upon the pivot bolt 3 which is inserted through the side of the car and the corner of the door, as clearly shown, the door being provided with an arcuate portion 4 concentric with the said pivot bolt so that the door may turn readily and at the same time fit closely to the floor of the car when it is extended across the door opening.

45 The pivot bolt 3 passes centrally through a disk or hanger 30 which is secured rigidly upon the inner side of the wall of the car.

The door is provided with an opening 31 in which the disk 30 fits closely but with sufficient freedom to permit the door to turn easily thereon. A washer 32 is fitted upon the bolt against the door and this washer is 60 larger than the disk so that it serves to hold the door thereon. A nut or other retaining device 33 is fitted on the end of the bolt or pin 3 to prevent separation of the parts and loss of the washer. This construction prevents grain working in behind the pivot mounting so as to interfere with the free rotation of the door.

55 The arcuate formation at the pivotal corner of the door is such that when the door is raised the end of the door will be spaced from the car floor and grain will not be wedged under the corner of the door when it is being raised to prevent it being turned to the perpendicular position and locked as 75 intended, to be held in place.

60 The outer side of the door is smooth and through the door, near the lower edge of the same, is formed an outlet opening 5 having horizontally disposed notches 6 at its ends. 80 A supplemental door 7 is slidably mounted upon the inner side of the door 2 and is supported and guided by ways 8 and 9, the upper way 8 consisting of an angle bar secured rigidly to the inner side of the door 85 and having a depending flange arranged to fit over the upper edge of the door and thereby hold the same in place, as shown most clearly in Fig. 5. The lower way 9 consists of a series of spurs or struck-up tongues 90 at the outer edge of an angle bar 10 secured rigidly to the door 2 at the lower edge of the same. The supplemental door is provided with a lug or handle 11 which is adapted to enter either slot 6 so that the door may be 95 moved to fully cover or fully uncover the outlet or opening 5.

65 The upper portion of the door 2 is reinforced by the bar 12 which is secured to the inner side of the door and extends longitudinally of the door and passes under the angle bar 8, the ends of the bar 12 being turned up and constructed to be rigidly secured to the door. A brace bar 13 is also secured to the door 2 at about the center of 100 the same and extends from the way or bar 8 to the upper edge of the door, the ends of this brace bar 13 being constructed with notches 14, as shown most clearly in Fig. 5. A loop or guide 15 is provided at that end 110

of the door 2 remote from the pivot 3 and a latch or bolt 16 is mounted to extend through this guide or loop and engage a keeper 17 on the side of the car. This latch 5 or bolt 16 has a down turned portion 18 at one end which is pivoted to the downwardly extending arm 19 of an angle lever 20 ful-crumed upon the door 2 near the guide 15. A pin 21 is also pivoted to the depending end 10 of the latch and plays within a guide and support 22 secured on the door 2, as shown, a platform or supporting ledge 23 being provided at the adjacent end of the bar 8 to support the pin 21 and the spring 24 coiled 15 around the same so as to prevent excessive distortion of the spring and also prevent the pin being drawn through the guide 22 so as to drop therefrom. The lever 20 is so disposed and so proportioned that its longer arm 20 may be very readily grasped when it is desired to release and open the door. When the free end of the lever rests in the upper notch 14 of the bar 13, the spring 24 will be 25 under some compression so that if the lever be lifted from its engagement with said notch and released, the spring will at once expand and force the latch into complete engagement with the keeper 17 and cause the lever to swing downwardly. When the lever 30 is in its lowermost position, it may be engaged in the notch 14 at the lower end of the bar 13 and will then aid in holding the latch in the keeper 17 so that accidental opening of the door will be prevented.

35 When the car is to be unloaded, the door 7 is slid so as to uncover the opening 5 whereupon a portion of the grain will flow from the car and the end of the lever will be accessible through the opening 5 so that 40 it may be released from the lower end of the bar 13. The grain will also fall away from the upper portion of the door to an extent sufficient to permit the lever to be reached and an upward swinging movement 45 imparted to the lever will then first withdraw the latch from the keeper 17 and then swing the door upon its pivotal support into the upright position, shown in Fig. 2, the latch springing into engagement with a keeper 25 upon the car near the roof thereof. The end of the lever may be easily reached 50 through the door opening so that it may be caused to engage in the notch 14 at what is

normally the lower end of the bar 13 and release of the door, with the consequent 55 dropping of the same before the grain is unloaded, will be prevented. A bracket 26 is provided upon the floor of the car to be engaged by the corner of the door so that the door will lie close to the side of the car in its 60 lowered position, and a similar bracket 27 is provided on the side of the car to receive the edge of the door when it is raised.

My device is obviously simple in the construction and arrangement of its parts and 65 may be readily applied to any grain car.

Having thus described the invention, what is claimed as new is:—

1. The combination of a latch, an angle lever pivoted at one end to the latch, means 70 to hold the lever in either latching or unlatching position, a guide, a pin slidably mounted in the guide and pivoted to the latch, and a spring around the pin between the guide and the latch and tending to hold 75 the latch in latching position.

2. The combination of a brace bar having notches in its ends, a latch, a lever pivoted at one end to the latch and adapted to have 80 its free end engaged in either notch in the brace bar, and means acting on the lever and the latch tending to hold the same in latching position.

3. The combination of a lever, a latch pivoted to the lever, a guide, a pin slidably 85 fitted in the guide and pivoted to the lever and the latch, a spring coiled around the pin between the latch and the guide, and a supporting ledge immediately below said spring. 90

4. The combination of a vertically disposed brace bar, a latch, a lever pivoted at one end to the latch and having its free end arranged to engage and be held by either 95 end of the brace bar, a guide, a pin slidably mounted at one end in said guide and having its opposite end pivoted to the latch, a spring coiled around said pin between the guide and the latch and normally holding the latch in projected position, and a longitudinally extending ledge below the spring 100 between the guide and the latch to support the spring at all times.

In testimony whereof I affix my signature.

EDWARD W. GROGAN. [L.S.]
